PERFUME COMPOSITIONS AND PERFUME ARTICLES CONTAINING ONE ISOMER OF AN OCTAHYDROTETRAMETHYL ACETONAPHTHONE

This application is a Division of copending application for U.S. Letters Patent Ser. No. 434,948 filed on Jan. 21, 1974 which is, in turn, a continuation-in-part of application for U.S. Letters Pat. Ser. No. 336,172 filed on Feb. 27, 1973, now abandoned.

10

BACKGROUND OF THE INVENTION

Materials which can provide amber fragrance notes are known in the art of perfumery. Many of the natural materials which provide such amber fragrances and contribute desired nuances to perfumery compositions such as ambergris can no longer be obtained or are high in cost or vary in quality from one batch to another and/or generally subject to the usual variations of natural products.

There is accordingly a continuing effort to find synthetic materials which will replace the essential fragrance notes provided by natural essential oils or compositions thereof having an amber aroma. Unfortunately, many of these synthetic materials either have the desired nuances only to a relatively small degree or else contribute undesirable or unwanted odors to the compositions. The search for materials which can provide a more refined amber fragrance has been difficult and relatively costly in the areas of both natural products and synthetic products.

The present invention provides a solution to the aforementioned problem by providing perfume compositions and perfumed articles which include isomer mixtures and a specific isomer which give rise to unexpectedly intense and persistent natural amber or fruity amber fragrance notes heretofore unknown in the acetonaphthone class of fragrance materials. Indeed, in the perfumers art, there is considerable need today for substituents having amber or fruity amber fragrance notes which are persistent. Especially desirable are materials which have an amber or fruity amber fragrance note which do not discolor with age. Such amber or fruity amber fragrance materials as stated above have a wide utilization in the preparation of finished perfume compounds. The materials when they are available from natural sources are subject to wide variations in quality, are expensive and are limited or often in critically short supply.

The prior art contains several disclosures of fragrance uses of compounds having structures similar to the compounds contained in the isomer mixtures useful in the practice of our invention and to the specific isomer useful in the practice of our invention.

British Pat. No. 896,039 entitled "Method of Producing Derivatives of the 1,1-Dimethyl-Octahydronaphthalene Series" discloses the generic process:

10

wherein R₂, R₃, and R₄ are disclosed to be same or different hydrogen atoms or alkyl and R₁ is disclosed to be hydroxy, alkyl or alkoxy. The British patent discloses this process to be useful for producing products "resembling the well known class of violet perfumes". Indeed, Example 5 of the British patent alleges that the compound 1,1,6,6-Tetramethyl-7-Ketomethyl-Octalin produced by (1) reacting myrcene and mesityl oxide thermally followed by (2) subsequent cyclization, has a pleasant "woody ambergris smell". However, a repetition of the teachings of this British patent gives rise to the following results:

b. T. Inukai and T. Kojima, *J.Org.Chem.*, 31,1121 (1966).

5 Lewis acid catalyzed reaction of isoprene with various acrylic acid derivatives.

9. Br. 1,076,304 (1965); *CA*, 68,49177 f (1968).

AlCl_3 catalyzed reaction of methyl acrylate, methyl methacrylate, or acrylonitrile with isoprene, piperylene, chloroprene, cyclopentadiene, or 1,3-butadiene. (cf. U.S. Pat. No. 3,390,169).

10. G. P. Kugatova-Shemyakina, L. I. Rozhkova, V. N. Gramenitskaya and V. M. Andreev, *J.Org.Chem. USSR*, 6,2459 (1970).

Catalysis of the reaction of acrolein or crotonaldehyde with isoprene or piperylene.

11. S. R. Wallis *J.Amer.Chem.Soc.*, 92,3218 (1970).

AlCl_3 catalyzed Diels-Alder reaction of butadiene with 2-phenyl-2-cyclohexenone.

20 In addition, Lewis acid catalyzed Diels-Alder reactions wherein the dienophile is α,β -disubstituted with alkyl groups are disclosed in our copending U.S. patent application Ser. No. 260,537 filed on June 7, 1972, now U.S. Pat. No. 3,869,516.

25 Further, cyclization reactions of Diels-Alder adducts of myrcene and a dienophile are set forth in U.S. Pat. No. 3,076,022. This patent discloses interalia, preparation of the thermal Diels-Alder adduct of myrcene and methyl isopropenyl ketone and subsequent acid cyclization 30 to a product said to possess "an intense ambergris-like note". Repetition of the process as disclosed gave rise to a product possessing fruity, woody, pineapple notes rather than an ambergris-like note.

35 Ohloff [Chemistry of Odoriferous and Flavoring Substances] pp. 185-240 (at page 192) *Fortschrifte & der Chemischen Forschung* Vol. 12, Part 2, 1969, discloses a compound having the structure:

Ohloff indicates that materials of this nature have "resiny odors" like olibanum, with amber type undertones.

THE INVENTION

This invention relates to the use of synthetic amber-like fragrance ingredients for perfumes and cosmetics. More particularly, the invention has to do with amber-like fragrance compositions for use in perfumery composed of octahydro-2',3',8',8'-tetramethyl-(2' or 3')-acetonaphthones in which a majority of said acetonaphthones contains the double bond in the 9'-10' position.

This invention also covers the use in perfumery of a novel isomer of octahydro-tetramethyl acetonaphthone having the structure:

wherein the dashed lines represent methyl groups "cis" to one another. The materials useful in our invention include isomer mixtures of octahydro-2',3',8',8'-tetramethyl-(2' or 3')- acetonaphthone having the generic structure:

wherein one of the wavy lines is a carbon-carbon double bond and the other of the wavy lines represent carbon-carbon single bonds. Such mixtures contain from 70 mole percent up to 99 mole percent of compounds having the generic structure:

Such a generic structure includes individually compounds having an acetyl group at the 2' position, compounds having an acetyl group at the 3' position and mixtures of such compounds. The generic structures set forth above are also intended to include geometric isomers wherein the acetyl group is "cis" to the methyl group on the carbon atom adjacent to that bonded to the acetyl moiety and where the acetyl group is "trans" to the methyl group on the carbon atom adjacent to that bonded to the acetyl moiety. The processes of our invention give rise to isomer mixtures containing the above-named isomers as well as the isomer having the structure:

The mixtures useful for carrying out our invention are produced by means of a two step reaction:

1. Reacting myrcene with 3-methyl-3-penten-2-one either:
  - a. In the presence of a Lewis acid at temperatures in the range of from 0° up to 50°C thereby producing a mixture of geometric isomers which are Diels-Alder adducts which are alkenyl acetyl dimethyl substituted cyclohexenes represented by the structure:

or:

- b. Reacting myrcene with 3-methyl-3-penten-2-one without using a catalyst at temperatures in the range of 120° up to 180°C forming a mixture of isomers (including geometric isomers) of alkenyl acetyl dimethyl substituted cyclohexenes having the generic structure:

- 25 2. Cyclizing the resulting substituted cyclohexenes (Diels-Alder adducts) by means of heating same in the presence of phosphoric acid or dilute sulfuric acid, (50-80%) or boron trifluoride or complexes thereof, e.g., boron trifluoride etherate.

- 30 30 The isomer mixtures produced thusly can be further separated by standard physical separation techniques (e.g., chromatographic techniques as set forth in Example XIV) or standard chemical techniques (e.g., oximation as set forth in Example XI) or they can themselves be incorporated into a wide variety of finished perfume compounds. It has been found that the materials useful for practicing this invention have persistent fragrances more fully described below which adapts them for incorporation into perfume compounds where a distinct amber of fruity amber fragrance note is required.

- 35 In the first of the two reactions of the process for preparing the materials useful in practicing our invention, myrcene and 3-methyl-3-penten-2-one are the reactants. Myrcene is generally available at purities of 70% and upwards and it can be used in this form. It is generally preferred in the practice of this invention to use commercial myrcene (approximately 77% purity) although, obviously, purified myrcene may be used. Such a purification is readily accomplished by fractional distillation. The initial reaction may be a thermal Diels-Alder reaction without the use of a Lewis acid catalyst at a temperature in the range of 120°-180°C. Preferably, but not necessarily, an antioxidant and polymerization inhibitor such as the mixture of beta-naphthylamine and pyrogallol may be utilized, as set forth in Example V of British Pat. No. 896,039. Upon performing the first step of the process of our invention by carrying out a thermal Diels-Alder reaction without the use of a Lewis-acid catalyst, the resulting material 55 will be a mixture of approximately 70 weight percent:

and 30 weight percent:

with unknown ratios of geometric "cis-trans" isomers of each. Where the initial Diels-Alder reaction is carried out using a Lewis acid catalyst, primarily geometric isomers having one basic structure are obtained, to 15 wit:

5

10

atmospheric pressure is 110°C. The quantity of solvent used in the cyclization reaction may vary from 0 weight percent up to 100 weight percent based on the amount of cyclohexene derivative being cyclized. It is preferred to use approximately 50 weight percent of solvent. In the cyclization reaction, the order of mixing reagents and solvents is not critical.

The length of time and temperature of the cyclization reaction will determine the percentage of the geometric isomers having the basic structure:

20

as compared with the geometric isomers having the other possible basic structures, namely:

25

30

35

40

75

80

85

90

95

100

Suitable Lewis acid catalysts are aluminum chloride, stannic chloride, titanium tetrachloride, boron trifluoride, and boron trifluoride complexes such as boron trifluoride etherates. The Lewis acid catalyst concentration workable in our process is from 0.5 up to 100 mole percent based on 3-methyl-3-penten-2-one with the preferred range being 3-8 mole percent. When using the Lewis acid catalyst, it is preferred that a solvent be used and suitable solvents are toluene, benzene and inert chlorinated hydrocarbon solvents such as chloroform and methylene chloride since they do not take part in the reaction. When using a Lewis acid catalyst, the first reaction is operated at a temperature in the range of 0° up to 50°C, preferably 35°-50°C. In both the thermal and catalytic Diels-Alder reactions, the mole ratio of myrcene to 3-methyl-3-penten-2-one may be varied from 1:3 to 3:1 or even higher, since the excess reagent may be recovered substantially quantitatively. However, for efficiency and economy as to time, the preferred mole ratio is from 1.1:1 up to 1.2:1. 45 The reagents and catalyst may be mixed in any order, however, it is preferred to sequentially add 3-methyl-3-penten-2-one and myrcene to a premix of the catalyst and solvent, the use of solvent in this reaction being preferred also.

The next reaction, following the Diels-Alder reaction, namely cyclization of the acetyl cyclohexene derivative (the Diels-Alder adduct), is accomplished by heating the cyclohexene derivative preferably with a mixture of an acid such as phosphoric acid, dilute sulfuric acid, boron trifluoride or boron trifluoride etherate in the presence of a solvent. The amount of acid cyclization agent may vary from 10 up to 100 weight percent based on the weight of the cyclohexene derivative to be cyclized. Preferably, the weight percent of acid should be between 40 and 50 weight percent. Preferably, an inert solvent having a boiling point at or about the desired reaction temperature is used in the cyclization reaction. The reaction temperature may be anywhere between 25°C and the reflux temperature of the reaction mixture. The preferred reaction temperature range is between 95° and 115°C and accordingly toluene is the preferred solvent since its boiling point at

(III)

(IV)

11

Periods of time of the order of 5-7 hours at temperatures of 70°-80°C. will yield a mixture wherein isomers having the basic structure (I) will be produced in a quantity of about 80-85%, the remaining isomers having the basic structures (II), (III) and (IV). However, if the cyclization reaction is run for a period of time of approximately 10 hours, and at 80°C., greater than 96% of the reaction product has a geometric isomer mixture having the basic structure (I). A temperature of reaction of 115°C coupled with a time of reaction of 4 hours will also yield a geometric isomer mixture more than 96% of the compounds of which have the basic structure (I). A time of reaction of 6 hours coupled with a reaction temperature of 115°C will give rise to a reaction product wherein more than 99% of the geometric isomers have the basic structure (I).

In the event that the first reaction, the Diels-Alder reaction, is carried out using a Lewis-acid catalyst, the mixture of isomers produced as a result of carrying out the second cyclization reaction on the resulting Diels-Alder reaction product has been found to contain a predominant quantity of an isomer having the structure:

Chromatographic techniques can then be effectively utilized to separate this novel isomer from the cyclization reaction mixture and such a technique is illustrated in Example XIV, infra. This isomer useful in carrying out our invention has a characteristic intense fruity-amber note. The above isomers are distinguishable from one another by examination of their respective NMR, infrared, and Raman spectra. The fact that the isomers indicated by formulae I and V have a tetrasubstituted double bond, and the isomers indicated by formulae II, III and IV have a double bond which is only trisubstituted and not tetrasubstituted is apparent from a study of FIGS. 1-6.

The two foregoing reactions may be performed in separate reaction vessels or, more preferably, they may be performed in the same reaction vessel whereby the Diels-Alder reaction and subsequent cyclization steps are carried out without isolating the intermediate Diels-Alder adduct, the cyclohexene derivative. Accordingly, when the Diels-Alder reaction is complete, the desired amount of acid is added without any additional solvents, and the reaction mixture is then stirred at the desired temperature until cyclization is complete.

When the cyclization reaction is substantially complete, the reaction mass is then washed and the organic layer is separated and distilled.

The distilled product may be used "as is" or it may be further purified by using gas chromatography tech-

12

niques and/or oximation (see Example XI) followed by recovery of the purified reaction product from the oxime.

The reaction product mixtures as well as the specific isomer of our invention are clear liquids with intense and persistent unique amber and fruity-amber odors. The isomer mixtures as well as the novel specific isomer of our invention are particularly suited to use as perfume materials in the preparation of perfume compositions. They are very well adapted to perfumery where an amber or fruity-amber aroma is required. The specific isomer useful in practicing our invention as well as the octahydro-tetramethyl-acetonaphthone isomer mixtures are particularly remarkable for their persistent fruity amber and amber odors. To make an amber or fruity amber type of perfume, the materials useful in practicing this invention can be combined with "auxiliary perfume adjuvants" including one or more of many types of odor materials such as bergamot oil, vetiver oil, patchouli oil, sandalwood oil, oakmoss and floral musk. The novel materials of this invention can also be combined with the customary perfume auxiliary adjuvants, such as natural oils, synthetic oils, aldehydes, ketones, carboxylic acid esters, aryl alcohols, alkanols, lactones, saturated hydrocarbons, unsaturated hydrocarbons, fixatives, solvents, dispersants, surfact active agents, aerosol propellants, and the like.

In the accompanying drawings forming part of this application, the figures which represent charts referred to in the examples are listed as follows:

FIG. 1 is a chart showing the nuclear magnetic resonance spectrum of peak No. 1 trapped by gas chromatography techniques from the product produced by the process of Example II, or the major peak trapped by gas chromatography techniques from the product of Example VII.

FIG. 2 is a chart showing the nuclear magnetic resonance spectrum of peak No. 2 trapped by gas chromatographic techniques from the material produced by the process of Example II.

FIG. 3 is a portion of the Raman spectrum of the major peak trapped by gas chromatographic techniques from the material produced according to the process of Example VII.

45 FIG. 4 is an infrared analysis spectrum of the material which is the major peak trapped by gas chromatographic techniques from the material produced according to the process of Example VII.

FIG. 5 is a nuclear magnetic resonance spectrum of the material produced according to the process of Example XIV.

FIG. 6 is the nuclear magnetic resonance spectrum of the product produced according to the process of Example XI.

55 The following examples serve to illustrate embodiments of our invention as it is now preferred to practice it. It will be understood that these examples are illustrative and the invention is to be considered restricted thereto only as indicated in the appended claims.

EXAMPLE I

13

3-Methyl-3-pentenone (2060 g, 95%) is added in 15 minutes to a suspension of aluminum chloride (90 g) in toluene (2 kg). The initial exotherm dies out after approximately 5% of the 3-methyl-3-pentenone is added. The mass is warmed to 35°C, and myrcene (3530 g, 77%) was added over a period of 2 hours with external cooling as needed to maintain the reaction mixture at 35°–40°C. The mixture is stirred at 35°–40°C for 2 hours, 27 g aluminum chloride is added, and the mass is stirred an additional 9 hours at 35°–40°C.

After standing overnight at room temperature, the mixture is washed at 40°C with 10% sodium chloride

14

solution and 15% sodium sulfate solution. The washed organic solution is mixed with 100 g triethanolamine, 100 g Primol (U.S.P. white mineral oil available from Exxon Incorporated of Linden, New Jersey) and 5 g Iono (registered trademark of the Shell Chemical Company; butylated hydroxy toluene) and is distilled rapidly at 2–3.5 mm Hg using a short column to give 3999 g of product, bp 146°–150°C/2–3.5 mm Hg.

EXAMPLE II

The product of Example I (3 kg, 98.7%) is added over a period of 45 minutes to a well-stirred mixture of 1.5 kg of toluene and 1.5 kg of 85% phosphoric acid maintained at 70°–80°C. The mixture is stirred vigorously at 70°–80°C for 5.5 hours and then is cooled and mixed with 3 kg of crushed ice. The organic phase is subsequently washed with 10% sodium chloride solution, 10% sodium carbonate solution and saturated sodium chloride solution. The washed organic solution is mixed with triethanolamine (100 g), Primol (50 g) and Ionol (3 g) and is rapidly distilled under reduced pressure using a short column.

Fractionation of the crude product gives 2604 g of a mixture of geometric isomers (bp 134°–135°C/2.8 mm Hg) having an intense amber aroma.

Using GLC analysis, this material shows two major peaks (Varian Aerograph model 200, 10' $\times$ $\frac{1}{4}$ ", 5% Carbowax K 20 M on chromosorb G, helium flow rate 80 cc per minute, temperature programmed 100°–200°C at 10°C/min.), Peak 1 = 93%, Peak 2 = 7%. Peaks 1 and 2 are trapped from the above column. The NMR spectra of the two peaks are quite different. The NMR analysis for Peak 1 is set forth in Table 1 and is as follows:

Ingredient	Amount (Grams)
4',5',6',7',8'-octahydro-2',3',8',8'-tetramethyl-2'-aceto-naphthalenes produced by the process of Example II (prior to GLC separation)	10
Cyclized Bicyclo C-12 material produced according to the process of Example IV of Canadian Patent 854,225 issued October 20, 1970	5
Iso Bornyl Cyclohexyl Alcohol	10
Benzyl Acetate	25
2-n-Heptyl Cyclopentanone	5
(TOTAL.)	353.3

50 The foregoing blend is evaluated and found to have a high degree of richness and persistence in its novel natural amber quality. This base composition can be admixed with aqueous ethanol, chilled and filtered to produce a finished cologne. The cologne so prepared 55 has an amber aroma leaning towards a woody amber note. The base composition can also be used to scent soap or other toilet goods such as lotion, aerosol, sprays and the like.

EXAMPLE IV

60 Into a 2 liter reaction vessel equipped with stirrer, thermometer and reflux condenser, the following ingredients are placed:

400 grams — Myrcene (77%)
 228 grams — 86.1% 3-Methyl-3-pentene-2-one
 1 gram — Ionol® (Registered trademark of the Shell Chemical Co.) (Butylated Hydroxy Toluene)
 50 grams — Toluene

21

The reaction vessel is operated at atmospheric pressure and the reaction mass is refluxed over a period of 28 hours at temperatures varying between 118° and 147°C. At the end of the 28-hour reaction period, the reaction mass is distilled through a fractionation column after initially being stripped of toluene. The fractionation reflux ratio is 4:1 and the distillation range is 112°-114°C vapor temperature at 0.8 mm. Hg. pressure. Yield 168 grams (55.7% of theory based on 3-methyl-3-pentene-2-one) of a mixture of Diels-Alder adducts having the generic structure:

EXAMPLE V

The Diels-Alder product of Example IV is added over a period of 45 minutes to a well-stirred mixture of 100 grams toluene and 100 grams 62% sulfuric acid maintained at 70°-80°C. The mixture is stirred vigorously at 70°-80°C for 6 hours and is then cooled and mixed with 1 kilogram of crushed ice. The organic phase is subsequently washed with 10% sodium chloride solution, 10% sodium carbonate solution and saturated sodium chloride solution. The washed organic solution is then mixed with triethanolamine (20 g), Primol (5 g) and Ionol (1 g) and is rapidly distilled under reduced pressure using a short column. In this way, a product is obtained containing only traces of uncyclized starting material and containing geometric isomers having the basic generic structure:

EXAMPLE VI

Into a 2 liter reaction flask equipped with reflux condenser, stirrer and thermometer, the following ingredients are placed:

500 grams — Diels-Alder adduct mixture prepared according to the process of Example IV
 250 grams — 85% phosphoric acid
 250 grams — toluene

The reaction mass is heated to reflux at atmospheric pressure (118°C) and maintained at reflux for a period of 3½ hours after which time the reaction mass was cooled down. The reaction mass is then washed with one 1 liter portion of water; then two 500 cc portions of water; then one 500 cc portion of 5% sodium carbonate and finally one 500 cc portion of saturated sodium chloride. The washed reaction mass is then stripped of solvent thereby giving rise to 445 grams of crude product. The crude product is then washed over and distilled through a fractionation column after adding to it 2 grams of calcium carbonate, 30 grams of Primol and 1

22

gram of Ionol at a vapor temperature of 124°-126°C and 2.1-2.8 mm. Hg. pressure.

IR, NMR and mass spectral analyses yield the information that the resultant product is a mixture of geometric isomers having chemical structures, 70% of which have the generic structure:

and 30% of which have the generic structure:

wherein one of the wavy lines in each of the above structures is a carbon-carbon double bond and the other of the wavy lines in each of the above structures represents a carbon-carbon single bond.

EXAMPLE VII

In Situ Preparation of 1', 2', 3', 4', 5', 6', 7', 8'-Octahydro-2', 3', 8', 8'-Tetramethyl-2'-Acetonaphthone Isomer Mixture From Myrcene and 3-Methyl-3-Pentene-2-One

Into a 5 liter reaction flask equipped with stirrer, reflux condenser, addition funnel and thermometer, the following ingredients are placed:

40 53 grams — aluminum chloride
 500 grams — toluene
 545 Grams of 3-methyl-3-pentene-2-one is then added through the addition funnel into the 5 liter reaction flask over a period of 5 minutes, the temperature of the
 45 mass rising to 41°C. Immediately thereafter, 975 grams of 77% myrcene is added, with stirring, to the reaction vessel over a period of 1 hour while maintaining the temperature of the mass at 40°-50°C. The reaction mass is then maintained at 40°-50°C for a period of 4½ hours after which period 300 grams of 85% phosphoric acid is added through the addition funnel. The reaction mass is then heated to 100°-115°C and maintained at that temperature for a period of 8 hours. At the end of the reaction, the reaction mass is washed with two 1
 55 kilo portions of 50°C water; then one 250 cc portion of 50°C 10% sodium carbonate solution; and finally one 500 gram portion of 50°C 15% sodium sulfate solution. After separation of the organic phase from the aqueous phase, 215 grams of triethanolamine is added to the reaction mass. The 5 liter reaction vessel is then equipped with stirrer, reflux condenser, thermometer and Bidwell trap and the mass is then heated to reflux (128°C) while removing solvent thereby gradually increasing the pot temperature to 165°C. After 8 hours, 60 sampling of the reaction mass and analysis thereof yielded the information that no labile organic halide is present in the reaction mass. The reaction mass is then stripped of solvent, the crude mass weighing 1410
 65 grams.

23

grams. The crude product is rushed over and then fractionated after adding 40 grams Primol, 1 grams Ionol and 10 grams calcium carbonate and purging with nitrogen, at a 1:1 reflux ratio at vapor temperature of 129°-131°C and 2.6-2.9 mm. Hg. pressure. Yield 845 grams.

The major peak is separated out by GLC analysis in accordance with the same procedure as is set forth in Example II. The Raman spectrum for the major peak (using a Raman spectrometer manufactured by Spex Incorporated of Plainfield, New Jersey) is, in part, set forth in FIG. 3. The Raman spectrum indicates a tetrasubstituted double bond at 1679 cm⁻¹ and a carbonyl group at 1711 cm⁻¹.

The infrared analysis for the major peak is set forth in FIG. 4.

The NMR analysis for the major peak is set forth in FIG. 1.

IR, NMR and Raman spectral analyses yield the information that the resulting product is a mixture of isomers having the generic structure:

EXAMPLE VIII

A perfume composition is prepared exactly as in Example III except that the mixture of isomers of 1', 2', 3', 4', 5', 6', 7', 8'-octahydro-2', 3', 8', 8'-tetramethyl-2'-acetonaphthones produced by the process of Example VII is applied in lieu of the mixture of Example II (prior to GLC separation).

This blend is evaluated and found to have a high degree of richness and persistence in its novel natural amber quality. This composition can be admixed with aqueous 95% ethanol (ratio: 95 parts ethanol:5 parts composition) chilled and filtered to produce a finished cologne. The cologne so prepared has an amber aroma leaning towards a woody amber note. The composition can also be used to scent soap or other toilet goods such as lotion, aerosol, sprays and the like.

EXAMPLE IX

Autoclave Reaction of Myrcene-and
3-Methyl-3-Pentene-2-One—Thermal Reaction
(Non-Catalytic)

Into a 1 liter stirred autoclave, the following ingredients are placed:

Myrcene (77%)	400 grams
3-Methyl-3-Pentene-2-One (90%)	220 grams
Ionol	1 gram
Toluene	20 grams

The autoclave is operated for a period of 10 hours at a temperature of 175°C and at a pressure of 2-3 atmospheres. At the end of the reaction period, the autoclave contents are cooled and fractionated. 141 Grams of product are collected from the fractionation which is carried out at a vapor temperature of 109°C and a pressure of 0.7 mm. Hg.

35

40

45

55

60

65

24

(reflux ratio 9:1). The resulting product is a mixture of isomers having the generic structure:

EXAMPLE X

Cyclization of Diels-Alder Adduct Mixture of Example IX

Into a 2 liter reaction flask, the following materials are charged:

Phosphoric Acid (85%)	150 grams
Toluene	275 grams

The toluene-phosphoric acid mixture is heated to 100°C. Over a period of 15 minutes, the Diels-Alder adduct isomer mixture of Example IX is added. The cyclization reaction is carried out over a period of 5 hours at temperatures in the range of 110°-115°C. At 50°C, the reaction mass is then washed with two 500 gram portions of water, one 500 gram portion of saturated sodium carbonate (to pH of 8.0) and one 15% solution of sodium sulfate. The toluene is then stripped off and reaction mass is rushed over at 1-1.5 mm. Hg. pressure and a vapor temperature of 110°-117°C. The rushed over material is then distilled at a vapor temperature of 128°-132°C and a pressure of 2.5 mm. Hg. (reflux ratio 9:1). GLC, NMR, IR and mass spectral analyses yield the information that the resulting product is a mixture of isomers having the generic structure:

EXAMPLE XI

Preparation of Oxime of 1', 2', 3', 4', 5', 6', 7', 8'-Octahydro-2', 3', 8', 8'-Tetramethyl-2'-Acetonaphthone and Regeneration of 1', 2', 3', 4', 5', 6', 7', 8'-Octahydro-2', 3', 8', 8'-Tetramethyl-2'-Acetonaphthone

A. PREPARATION OF OXIME

In a 2 liter flask is placed 1000 ml of 95% aqueous ethanol and 61 gms. of hydroxylamine sulfate. The reaction mass is stirred while a solution of 30 gms. of sodium hydroxide in 30 gms. of water is added slowly. After an additional 35 minutes of stirring, the reaction mass is filtered to remove the suspended sodium sulfate.

The resulting alcoholic solution of hydroxylamine is charged to a 2 liter three neck flask and 115 gms. of material prepared as in Example VII (prior to GLC separation) is added. The resultant mixture is stirred vigorously at reflux for approximately 8.5 hours. The

solution is cooled to room temperature and the resulting crystals are filtered and air dried to give 70 gms. of oxime. The oxime is crystallized twice from toluene (2-3 ml toluene per gram oxime) to get 50 gms. purified oxime.

B. REGENERATION OF 1', 2', 3', 4', 5', 6', 7', 8'-OCTAHYDRO-2', 3', 8', 8'-TETRAMETHYL-2'-ACETONAPHTHONE

A mixture of 50 gms. of the recrystallized oxime produced in Part A herein, 250 gms. of 20% weight/weight sulfuric acid, and 500 gms. of 95% aqueous ethanol is stirred at reflux for 4.5 hours. The mixture is washed with 2500 ml of 10% sodium hydroxide solution and then with water. Toluene (100 ml) is added to the organic layer and the material is stripped under reduced pressure (10-20 ml Hg pressure) to remove traces of water. The washed and dried product is then distilled to give 30 gms. of product which is essentially identical to the product of Example XIV by comparison of NMR spectra and GLC elution times. The NMR analysis of this material is set forth in FIG. 6.

This material is evaluated as being a very clean version of the material prepared in accordance with the process of Example VII, significantly better than the material which contains other isomers.

5 to a well stirred mixture of 1000 gms. of toluene and 145 gms. of boron trifluoride diethyl ether complex in a 3. liter reaction vessel equipped with stirrer, reflux condenser, thermometer, and addition funnel. The reaction mass is then maintained at 48°-51°C over a period of 13 hours and is then cooled to less than 25°C with stirring. While being maintained at 25°C, 600 gms. of 10% aqueous sodium hydroxide is added to the reaction mass. The resulting organic layer is then washed with 10% sodium hydroxide and water. The reaction mass is then stripped of solvent thereby yielding 332 gms. of crude product. The crude product is fractionated at a vapor temperature of 125°-128°C and a pressure of 2.2 mm. Hg. after 30 gms. of Primol, 1 gm. of Ionol and 5 gms. of calcium carbonate is added thereto. 15 In this way, a product is obtained containing geometric isomers having the basic generic structure:

20

25

EXAMPLE XII

A perfume composition is prepared exactly as in Example III except that the mixture of isomers of 1',2',3',4',5',6',7',8'-octahydro-2',3',8',8'-tetramethyl-2'-acetonaphthones produced by the process of Example X is employed in lieu of the mixture of Example II.

This blend is evaluated and found to have a high degree of richness and persistence in its novel natural amber quality. This composition can be admixed with aqueous ethanol, chilled and filtered to produce a finished cologne. The cologne so prepared has a citrus aroma leaning towards an amber note. The composition can also be used to scent soap or other toilet goods such as lotion, aerosol, sprays and the like.

30

35

40

EXAMPLE XIV

The major GLC peak of the product of Example VII is trapped from a 500' × 0.03", SF96 (a non-polar silicone polymer manufactured by Analabs Inc. of P.O. Drawer 5397, Hamden, Connecticut 06518) column at 185°C isothermal. This peak is 86.1% of the total material produced (according to GLC on a similar column). The trapped peak is 99.9% one peak when rechromatographed on a 500' × 0.03", SF96 column programmed 80°-185°C at 4°C/min.

The trapped material is submitted for NMR analysis and the results are as follows:

Chemical Shifts

δ2.09, 3H, sharp singlet

Interpretation

δ2.40-1.20, 11H, complex multiplet

δ1.01, 3H, sharp singlet
δ0.90, 6H, broadened singlet

Chemical Shifts

Interpretation

80.80, doublet, $J = 7$ cps
 80.82, doublet, $J = 7$ cps

The NMR analysis is set forth in FIG. 5.

EXAMPLE XV

A perfume composition is prepared exactly as in Example III except that the tetramethyl acetonaphthone isomer having the structure: 20

produced by the process of Example XI or Example XIV is employed in lieu of the mixture of Example II.

The foregoing blend is evaluated and found to have a high degree of richness and persistence in its novel natural amber quality. This composition can be admixed with aqueous 95% ethanol (ratio: 95 parts ethanol: 5 parts composition) chilled and filtered to produce a finished cologne. The cologne so prepared has an amber aroma leaning towards a woody amber note. The composition can also be used to scent soap or other toilet goods such as lotion, aerosol, sprays and the like.

EXAMPLE XVI

Preparation of a Soap Composition

A total of 100 gms. of soap chips produced from unperfumed sodium based toilet soap made from tallow and coconut oil are mixed with 1 gm. of the perfume composition set forth in Example XV until a substantially homogeneous composition is obtained. The soap composition manifests a characteristic amber aroma.

EXAMPLE XVII

Preparation of a Soap Composition

A total of 100 gms. of soap chips produced from unperfumed sodium based toilet soap made from tallow and coconut oil is mixed with 1 gm. of the isomer produced using the process of Example XI or Example XIV until a substantially homogeneous composition is obtained. The soap composition manifests a "fruity amber" character.

EXAMPLE XVIII

Preparation of a Detergent Composition

A total of 100 gms. of a detergent powder sold under the trademark "RINSO" are mixed with 0.15 gms. of a

perfume composition containing the mixture obtained in Example XV until a substantially homogeneous composition having an amber fragrance is obtained.

EXAMPLE XIX

Preparation of a Cosmetic Base

A cosmetic powder is prepared by mixing 100 gms. of talcum powder with 0.25 gms. of the perfume composition of Example XV in a ball mill. A second cosmetic powder is similarly prepared except that the mixture produced in Example XV is replaced with the product produced in Example XI or Example XIV. The cosmetic powder containing the material of Example XV has an amber fragrance. The cosmetic powder produced using the material produced in Example XI or Example XIV has a fruity amber character.

EXAMPLE XX

Liquid Detergent

Concentrated liquid detergents with fruity amber odor containing 0.2%, 0.5% and 1.2% of the product produced in accordance with Example XI or Example XIV are prepared by adding the appropriate quantity of the specific isomer so produced to liquid detergent known as P-87. The fruity amber aroma of the liquid detergent increases with increasing concentration of the isomer of Example XI or Example XIV.

EXAMPLE XXI

Preparation of Cologne and Handkerchief Perfume

The composition of Example XV is incorporated in a cologne having a concentration of 2.5% in 85% aqueous ethanol; and into a handkerchief perfume in a concentration of 20% (in 95% ethanol). The use of the composition of Example XV affords a distinct and definite amber aroma to the handkerchief perfume and to the cologne.

EXAMPLE XXII

Preparation of Cologne and Handkerchief Perfume

The specific isomer produced by the process of Example XI or Example XIV is incorporated into a cologne having a concentration of 2.5% in 85% ethanol; and into a handkerchief perfume in a concentration of 10% (in 95% ethanol). The specific isomer having the structure:

produced in Example XI or Example XIV affords a distinct and definite fruity amber aroma to the hand-kerchief perfume and to the cologne.

What is claimed is:

1. A process for altering the aroma properties of consumable material selected from the group consisting of perfume compositions and perfumed articles which comprises adding thereto a small but effective amount of an amber-like fragrance composition containing a major proportion of 1',2',3',4',5',6',7',8'-octahydro-2',3',8',8'-tetramethyl acetonaphthone isomers produced by a synthesis comprising the steps of:

i. Admixing at a temperature of from about 0°C up to about 50°C myrcene and 3-methyl-3-pentene-2-one in the presence of a Lewis acid catalyst thereby forming an acetyl substituted cyclohexane mixture, and

ii. Cyclizing the resulting acetyl substituted cyclohexane mixture with a cyclizing agent selected from the group consisting of concentrated phosphoric acid, sulfuric acid, boron trifluoride and complexes of boron trifluoride.

2. A process for altering the aroma properties of consumable material selected from the group consisting of perfume compositions and perfumed articles which comprises adding thereto a small but effective amount of an amber-like fragrance composition containing a major proportion of 1',2',3',4',5',6',7',8'-octahydro-2',3',8',8'-tetramethylacetonaphthone isomers produced by a synthesis comprising the steps of:

i. Admixing at a temperature of from about 120° up to 180°C, myrcene and 3-methyl-3-pentene-2-one thereby forming a mixture of acetyl cyclohexene isomers, and

ii. Cyclizing the resulting acetyl cyclohexene isomers with a cyclizing agent selected from the group consisting of concentrated phosphoric acid, sulfuric acid, boron trifluoride and complexes of boron trifluoride.

3. The process of claim 1 wherein the first step of the synthesis and the second step of the synthesis are carried out in the same reaction vessel, without isolating the acetyl substituted cyclohexene isomer mixture.

4. The process of claim 2 wherein the first step of the synthesis and the second step of the synthesis are carried out in the same reaction vessel, without isolating the acetyl substituted cyclohexene isomer mixture.

5. The process of claim 1 wherein the first reaction step of the synthesis is carried out at a temperature in the range of from 35° up to 50°C and the second reac-

tion is carried out in the presence of toluene as solvent at a temperature of from 95° up to 115°C.

6. A perfume composition comprising an effective perfuming amount of an amber-like fragrance composition containing a major proportion of 1',2',3',4',5',6',7',8'-octahydro-2',3',8',8'-tetramethyl acetonaphthone isomers produced by a synthesis comprising the steps of:

i. Admixing at a temperature of from about 0° up to about 50°C myrcene and 3-methyl-3-pentene-2-one in the presence of a Lewis acid catalyst thereby forming an acetyl substituted cyclohexene mixture, and

ii. Cyclizing the resulting acetyl substituted cyclohexene mixture with a cyclizing agent selected from the group consisting of concentrated phosphoric acid, sulfuric acid, boron trifluoride and complexes of boron trifluoride,

and an auxiliary perfume adjuvant.

7. A perfume composition comprising an effective perfuming amount of an amber-like fragrance composition containing a major proportion of 1',2',3',4',5',6',7',8'-octahydro-2',3',8',8'-tetramethyl acetonaphthone isomers produced by a synthesis comprising the steps of:

i. Admixing at a temperature of from about 120° up to 180°C, myrcene and 3-methyl-3-pentene-2-one thereby forming a mixture of acetyl cyclohexene isomers, and

ii. Cyclizing the resulting acetyl cyclohexene isomers with a cyclizing agent selected from the group consisting of concentrated phosphoric acid, sulfuric acid, boron trifluoride and complexes of boron trifluoride,

and an auxiliary perfume adjuvant.

8. A perfume composition comprising an effective perfuming amount of a compound having the structure:

and an auxiliary perfume adjuvant.
